UNITED STATES PATENT OFFICE.

WILLIAM DAVIDSON, OF ATLANTA, GEORGIA

COMBINED MAIL-BAG CATCHING AND DELIVERING APPARATUS AND SEMAPHORE-MAST.

No. 835,503.

Specification of Letters Patent.

Patented Nov. 13, 1906.

Application filed September 8, 1906. Serial No. 333,785.

To all whom it may concern:

Be it known that I, WILLIAM DAVIDSON, a citizen of the United States, residing at Atlanta, in the county of Fulton and State of Georgia, have invented certain new and useful Improvements in a Combined Mail-Bag Catching and Delivering Apparatus and Semaphore-Mast, of which the following is a specification.

This invention relates to improvements in devices for delivering mail-bags to and receiving mail-bags from moving trains and also having the same combined wherever circumstances will permit with a semaphore-mast, the said mast acting for one mast for both the mail-crane and semaphores. I attain these objects by the mechanism illustrated in the accompanying drawings, in which—

Figure 1 is a side elevation of the combined catcher and deliverer, showing the mail-bags 23 and 28 in position to be caught and delivered, also part of the end of a mail-car and the mast 1, which supports the catching and delivering device, and the extension 4 to mast 1, which supports the signals, usually called "semaphores." Fig. 2 is a back elevation showing part of mast 1 and the reversible fork 17 and crank 16 and rod 18, which are used to operate or reverse the said fork 17 and pin 19, which is to hold rod 18 in position after the said fork has been reversed. Fig. 2 also shows part of the wire-netting that the mail-bag 28 will fall against when caught by fork 17. Fig. 3 is a side elevation of part of the side of a mail-car, showing the door to car and the catcher 20 on the car, and the spring-hooks 26 and 27 to hang the mail-bag 28 to be delivered on, and the rope 22, which is fast to mail-bag 28 and extending over to rod 21; also, the ball 22^b on the end of rope 22; also, the spring 22^c, which holds rope 22; also, mail-bag 28, which is in position to be delivered at the station. Fig. 16 is a modification of the arm 3, showing how it can be connected to any mast by means of the split collar 2^a and 2^b. Figs. 4, 5, 6, 7, 8, 9, and 11 are detailed views of the several parts.

Similar numerals refer to similar parts through the several views.

The mast 1, T 2, arm 3, and extension 4 constitute the framework of the apparatus,

the said mast 1 being made fast to the ground by a bed-plate or by setting it into the ground in a bed of concrete.

55

Fig. 1 shows the mail-bag 23 in position to be caught by catcher or hook 20, which is fastened to the side of mail-car. When the said hook 20 catches the bag 23, the spring-clamps 25 and 25^a, which are on the ropes 12 and 14, will close by having a pull put on the rings 24 and 24^a. This will allow the mail-bag 23 to free itself from clamps 25 and 25^a and go on with the catcher-arm 20. The weight 11 will then drop to the ground, as shown by dotted lines. This will pull the spring-clamp 25 and ropes 12 and 13 back in the position indicated by the dotted lines from 9 to 8^a. The said spring 25 and ropes 12 and 13 will be back out of the way of all passing trains. The clamp 25^a and ropes 14 and 14^a will fall back to the position indicated by the dotted lines 14 and 25^a.

60

While the arm 20 is up to catch bag 23 the wire or rod 21, which is fastened to arm 20, 75 will slide through the slot in fork 17, which is pivoted to mast 1. The slot 17^a in the fork 17 is made just a fraction larger than the wire 21 and rope 22, so that the said wire and rope will slide into the said slot 17^a. The end of 80 the rope 22 is made larger than the body of the rope by means of a knot or by putting a ball 22^b of some kind on the end of the said rope 22, so that when the rod 21 reaches the curve in fork 17 the knot or ball on the end of 85 rope 22 will prevent the rope 22 from passing on through the said slot 17^a and the said knot or ball 22^b will slide off of wire 21 and remain behind the fork 17. This will pull the rope 22 from the clamp 22^a and then pull the bag 90 28 from the spring-hooks 26 and 27, which are fastened to the side of the car and are to hold the ends of the said bag 28. I have two of the said spring-hooks 26 and 27 on each side of the door, so as to always use the two 95 back of the catcher to keep the bag out of the way of the arm 20. Now when mail-bag 28 is pulled from the hooks 26 and 27 it will fall against the wire-netting 30, (shown in Fig. 2,) as the distance from the hook 17 to the 100 ground is greater than the length of rope 22. The mail-bag 28 will not fall to the ground, but will hang on fork 17 and rope 22. Now to remove the bag 28 from the fork 17 pull

pin 19, Fig. 2, out of rod 18 and mast 1. This will allow the fork 17 to turn the forked ends 17^b, Fig. 7, down. Then pull on bag 28, and the rope 22 will slide out of the slot 17^a, Fig. 5 7. The ropes 12, 13, 14, and 14^a can be of any good strong wire, hemp, or other rope that is strong enough to stand the strain; but I prefer a one-fourth-inch copper-wire rope. The arm 3 should be placed high enough so 10 that no one can hit the said arm 3 when passing it on a car or engine. The pulley 8^a is fastened to the arm 3 at or near the end from the mast 1. The bracket or hollow bolt 7 is fastened to mast 1 and has a pulley 8 in it. 15 The pulleys 8 and 8^a have rope 12 to pass over them.

If this mail-crane is located where there is a semaphore-mast required, then the mast 1 can be extended up by adding piece 4 onto 20 the T 2 and putting the semaphores 5 and 5^a and light 6 on top of the extension 4. We then have a combined crane and semaphore-mast.

While the mail-bag 23 is hanging and being 25 caught weight 11 is held in position by an eyebolt 15, Figs. 1 and 6. The said eyebolt 15 has a slot in it, so that the rope 12 can be removed from the said eyebolt 15 when necessary. The hook 9, Figs. 1 and 5, is fastened 30 to mast 1 and is to hold rope 13 in position. 14^b is an eyebolt having spurs and is fastened to a tie. The spring-clamp 25, Figs. 1 and 4, is used on the ropes 12 and 14 to hold the ends of mail-bag 23. The said spring-clamp 25 is 35 made of steel wire and is curved around at the center to form an eye. The legs then extend down parallel a short distance and then curve out, forming shoulders on which the ring 24 can rest. They then extend on far- 40 ther and nearly parallel with one another a sufficient distance to give plenty of leverage to be able to force them together to get the ring 24 on the spring-clamp. If the legs of the said spring 25 are not extended beyond 45 the shoulders that support the ring 24, then the ends or legs cannot be forced together with the hands and force them in the ring. I have made some and know by experience. So my spring-clamp is an improvement over 50 all spring-clamps having forks or legs and is used to hold the ends of mail-bags. Fork 17 is fastened to shaft 16 and is free to be reversed or moved around by rod 18. Shaft 16 is fastened to mast 1 and sits at right angles 55 to the track. Wire-netting 30 is fastened to the frame formed by rods 29 and 29^a. The said netting 30 will extend out on either side of the fork 17 a distance a little greater than the length of the rope 22, so that the bag 28 60 will always hit the said netting 30 when pulled from the side of the car or hooks 26 and 27.

Figs. 10 and 11 shew a means by which any

mast or post can be used for a mail-crane by attaching the arm 3 and connection to the 65 said mast or post. Figs. 8 and 9 show the spring-hooks 27 and 26, which are fastened to the side of the car and a pair on each side of the car-door. To hang the bag on hook 27, mash down on the handle 27^a and then slip 7^c the ring on the end 27^b. Then loose the end 27^a, and the springs 27^b will force the end 27^b down and hold the ring. The end of hook 27^c is made tapering, so the ring can slide off of it easily when the bag 28 is caught. To 75 hang the lower end of bag 28 on hook 26, just push the ring down behind the spring 26^a, Fig. 9. Now hang the ball 22^b on rope 22 onto the wire 21 and then slip rope 22 in the wire-clamp 22^a. The mail-bag 28 is now 80 ready to be delivered or caught by the fork 17. Now to hang up mail-bag 23 move rope 12 out of eyebolt 15, so that weight 11 can go up mast 1. Then unhook rope 13 from bolt 10 and throw the rope 13 off of 85 hook 9 and pull down the spring-clamp 25 and weight 11 will go up mast 1. Force the ends of clamp 25 together and slip them in ring 24. Then put ring 24^a onto spring 25^a. Then let the bag 23 go up and the weight 11 90 will come down to eyebolt 15. Put rope 12 in eyebolt 15. Then pull down on rope 14 until weight 11 goes close up to eyebolt 15. Then fasten rope 14 to bolt 14^b. Then throw rope 13 over hook 9 and fasten the lower end 95 of rope 13 to bolt 10. Then catch hold of rod 18 and pull fork 17 up so the end will point in the opposite direction from the direction the train is moving. Then fasten rod 18 by slipping pin 19 into the rod 18 and mast 1. 100 Everything is now ready to catch and deliver mail-bags 23 and 28.

As the law requires that all mail-cranes have a light on them when in use at night, the semaphore-light 6 can be used for both the 105 mail-crane light and semaphore-light.

In case it is desired to deliver more than one mail-bag at a station any desired number of bags may be supported on hooks 26 and 27, a pair of hooks for each bag being applied 110 to the side of the car. In this arrangement a single rope 22 may be engaged or wrapped around all of the bags. A number of bags can thus be delivered at one time at any desired station.

The spring clamping device shown in Fig. 9 is constructed of a back plate 26, having upper and lower flanges; a post 26^c, pivoted in said flanges and having secured to it a hook 26^a, provided with coils 26^b, engaging 120 with a short cross-pin, as clearly shown in Fig. 9. By providing a pivoted post the spring-clamp is free to turn and adjust itself to the pull of the rope attached to the bag either to the right or left as the bag is engaged by the fork 17.

The clamping device shown in Fig. 8 is composed of a back plate having flanges in which is pivoted the post 27^a, having on it coiled springs 27^b and also provided with a cross-bar 27^c, having at one end a tapering end or pin 27^d. This tapered end 27^d bears upon the upright flange of the plate and is adapted to receive a ring 27^e on a bag. The outer end 27^a of the bar serves as a handle for pressing it down and opening or raising the pointed end 27^d to receive the ring.

Having described my invention, what I claim, and desire to secure by Letters Patent, is—

1. The combination in a mail-bag deliverer, with a semaphore-mast, of an adjustable and detachable supporting-arm, whereby mail-bag-delivery apparatus may be attached to any semaphore-post, or mast already in position, substantially as described.

2. The combination with a semaphore-mast, of a detachable supporting-arm having a clamping device therefor, pulleys attached to said arm and adapted to carry a rope for supporting a mail-bag at one end and having a weight at the other end, substantially as described.

3. The combination with a post or mast, of a supporting-arm, a rope-guide attached to the mast having a pulley, a pulley at or near the outer end of the arm, a rope passing over the pulleys and having at its inner or delivery end a spring-clamp adapted to engage a ring on a bag, and at its outer end a weight and means for holding the rope and weight in position, substantially as described.

4. The combination with a post or mast of a supporting-arm, pulleys on the post and arm, a rope passing over the same and having at its inner end a clamping device for engaging a ring on a bag, and at its outer end a weight, means for holding or restraining the rope and weight, and a second rope attached at or near said clamp and passing over a hook or bracket on the post and means for attaching its other end near the ground, substantially as described.

5. The combination with a post or mast of a supporting-arm, pulleys on the post and arm, a rope passing over the same and forming a flexible connection from the arm to a mail-bag, a clamping device at its inner end, a lower rope forming a flexible connection from the ground or base up to the lower end of the bag and having a clamping device therefor, a second rope attached near the upper clamp and passing over a bearing on the post, and a third rope attached near the lower clamp and to the post, substantially as described.

6. In mail-bag-delivering apparatus, the combination with a post, an arm and pulleys thereon, of a flexible connection from the

arm having at its ends a spring-clamp, composed of a coiled wire with projecting fork 6^a ends having offsets or shoulders for engaging a ring on a bag, a second and lower flexible connection secured to a base and having at its free end a similar spring-clamp for engaging a ring on the lower end of a bag, and means for operating said rope connections, substantially as described.

7. In a mail-bag-delivering apparatus, a detachable supporting-arm consisting of a split collar having flanges for bolts, and one part having a projection, an arm adapted to be secured to, or in said projection, and means for carrying and guiding a rope, substantially as described.

8. In a mail-bag-delivering apparatus, a spring clamping device composed of spring-wire coiled centrally to form an eye, and having projecting fork ends provided with outwardly-curved shoulders and comparatively long ends extending from said shoulders for engaging with the interior of a ring whereby a bag with a ring may be readily attached to or detached from said clamp, substantially as described.

9. In a mail-bag catching and delivering apparatus, a pair of spring-hooks secured to the side of the car, in position to engage with the upper and lower ends of a mail-bag, in combination with a catcher-arm and wire extension engaged therewith, a wire or rope connecting therewith and with the bag and having a knot or enlargement and a fork device connecting with a post or mast for engaging said wire extension and rope, substantially as described.

10. In a mail-bag catching and delivering apparatus, the combination with a post or mast of a swinging or pivoted fork, a catcher-arm on a car, a rope having a knot or enlargement connecting with the outer end of said arm, and spring-hooks on the car for engaging and holding the ends of a bag, said rope which connects with the arm also being arranged to connect with the bag, whereby the bag may be delivered from a passing car, substantially as described.

11. In a mail-bag catching and delivering apparatus, the combination with a post or mast having a pivoted and swinging fork and means for reversing and holding it in position, of a yielding screen or stop device extending on opposite sides of the mast for arresting a mail-bag when caught by the fork, means on a car for supporting a bag and catcher-arm, a rope connected therewith having an enlargement and connecting with the bag, substantially as described.

12. In a mail-bag catching and delivering apparatus, a spring-engaging hook for holding the end of a mail-bag on a car, consisting of a back plate, a turning post therein, and a

1
spring clamping-hook attached to the post, substantially as described.

13. In a mail-bag catching and delivering apparatus, a spring-engaging device for engaging a ring on the end of a mail-bag, consisting of a back plate having flanges, a post pivoted in said flanges and having springs, also a cross-bar serving as a handle on one side and as a pin bearing on the plate and

adapted to engage a ring of a bag, substantially as described.

In testimony whereof I affix my signature in presence of two witnesses.

WILLIAM DAVIDSON.
